UNITED STATES PATENT OFFICE.

WALLACE B. TYRRELL, OF DELAVAN, WISCONSIN, ASSIGNOR TO BRADLEY KNITTING COMPANY, OF DELAVAN, WISCONSIN, A CORPORATION OF WISCONSIN.

DESIGN FOR A KNITTED CAP.

58,957.

Specification for Design.

Patented Sept. 6, 1921.

Application filed June 8, 1921. Serial No. 476,098. Term of patent 14 years.

To all whom it may concern:

Be it known that I, WALLACE B. TYRRELL, a citizen of the United States, residing at Delavan, in the county of Walworth and State of Wisconsin, have invented a new, original, and ornamental Design for Knitted Caps, of which the following is a specification, reference being had to the accompanying drawing, forming part thereof.

Fig. 2 is a front elevation of the same.

I claim:

The ornamental design for a knitted cap, as shown.

WALLACE B. TYRRELL.
